DESIGN FOR A DRESS OR SIMILAR ARTICLE

Herman Beispel, New York, N. Y.

Application July 20, 1942, Serial No. 107,617

Term of patent 3½ years

To all whom it may concern:

Be it known that I, Herman Beispel, a citizen of the United States of America, residing in New York city, county of New York, N. Y., have invented a new, original, and ornamental Design for a Dress or Similar Article, of which the following is a specification, reference being had to the accompanying drawing, forming part thereof.

In the drawing:

The dress is slit and gathered at the front of the waist portion and from which extend the tie members for the bow shown in tied condition in the drawing.

I claim:

The ornamental design for a dress or similar article, substantially as shown and described.

HERMAN BEISPTEL.
